ADVERTISING SIGN

Clyde E. Shadwell, Gary, Ind., assignor to Vibra-Sign Company, Incorporated, Elgin, Ill., a corporation of Illinois

Filed Apr. 2, 1965, Ser. No. 84,582

Term of patent 3½ years

(Cl. D1—12)

FIG. 1 is a front elevational view of an advertising sign embodying my new design, it being understood that the suspended disks are continuous throughout the area indicated in broken lines;

FIG. 2 is a side elevational view thereof;

FIG. 3 is a top plan view thereof;

FIG. 4 is a rear elevational view thereof; and

FIG. 5 is a bottom plan view thereof.

The dominant features of my design reside in the portions shown in full lines.

I claim:

The ornamental design for an advertising sign, substantially as shown and described.
